(57) **CLAIM**

The ornamental design for a container for oil and vinegar, as shown and described.

DESCRIPTION

FIG. 1 is a front elevational view of my design for a container for oil and vinegar;

FIG. 2 is a top plan view thereof;

FIG. 3 is a bottom plan view thereof;

FIG. 4 is a front elevational view thereof cut longitudinally through the center, and in section; and,

FIG. 5 is another elevational view thereof rotated 45° from the position shown in FIGS. 1 and 4, and again cut longitudinally through the center and in section.

The broken line showing of the threaded end, spray nozzle and suction duct is for illustrative purposes only and forms no part of the claimed design.
